WATCH BRACELET
Charles L. Matson, Chicago, Ill.

Application February 9, 1945, Serial No. 576,935

3 Claims. (Cl. 63—5)

My invention relates to bracelets employed for the retention of wrist watches, and more particularly to bracelets of the coil spring type, and one object of the invention is to provide a bracelet of this kind which cannot be stretched beyond a given limit, preventing the excessive expansion or loosening of the spring.

A further object of the invention is to provide a bracelet of the above character in which a series of external blocks provide a passage and housing for the spring, whereby to keep the latter from rubbing or pinching the skin or pulling hairs which enter the bracelet.

Another object of the invention is to provide simple and effective means to keep the blocks referred to sufficiently separated to prevent hairs from becoming caught therebetween and pulled on the movement of the bracelet.

An important object of the invention is to construct the improved bracelet along lines of simplicity, compactness and beauty.

With the above objects in view and any others which may suggest themselves from the description to follow, a better understanding of the invention may be had by reference to the accompanying drawing, in which—

Fig. 1 is a plan view of the bracelet as attached to a wrist watch;

Fig. 2 is a cross-section of the bracelet as constructed with an oval-coil spring;

Fig. 3 is a view similar to Fig. 2, showing the bracelet constructed with a round-coil spring;

Fig. 4 is an enlarged longitudinal section of a portion of the bracelet where it connects with the wrist watch; and

Fig. 5 is a section on the line 5—5 of Fig. 4.

Referring specifically to the drawing, it is noted that the bracelet is basically in the form of a coil spring 10, whose coils may be oval—as indicated in Fig. 2—or circular—as shown in Fig. 3.

Figs. 4 and 5 show that the end coils of the spring 10 are tightly driven into a socket 11 serving as a coupling with one side of the watch 12. Usually, this type of coupling terminates with a cross-tube 13 through which passes a pintle 14 carried by side lugs 15 of the watch.

Two sockets of the above character are applied endwise of the spring; and the latter receives a series of blocks 16 between the sockets. As shown in Figs. 2 and 3, these are of solid construction and substantially flat form to lie closely around the wrist. They thus keep the spring 10 raised from the skin, relieving the latter from chafing, the trapping of hairs between the spring coils and the pulling of the hairs when the bracelet is bent and stretched about the wrist, thereby slightly increasing the spring load. The external blocks 16 are of a limited extent, so as to leave

Finally, the block series conceals the spring and its mechanical contents, so that nothing is visible that may detract from the ornamental appearance of the bracelet.

While I have described the invention along specific lines, various minor changes or refinements may be made therein without departing from its principle, and I desire to consider such changes and refinements as coming within the scope and spirit of the appended claims.

I claim:

1. A watch bracelet of coil spring form, a series of blocks strung on the spring, and pins extended from one block to meet the next and form a space endwise between them.

2. The structure of claim 1, said blocks being flattened to present broad outward and inward surfaces when the bracelet is worn on the wrist, and said pins being extended at points on opposite sides of the spring near the narrow sides of the blocks.

3. The structure of claim 1, said blocks being flattened to present broad outward and inward surfaces when the bracelet is worn on the wrist, and said pins being extended at points on opposite sides of the spring and substantially even with one of said surfaces.
